Britain, Conn., a corporation of Connecticut

Application September 10, 1948, Serial No. 48,626

15 Claims. (Cl. 70—211)

1

My invention relates to a latch-actuating and dogging mechanism.

It is an object of the invention to provide an improved device in the character indicated.

It is another object to provide an improved dogging mechanism complete in itself and readily adaptable to a more or less conventional latch mechanism.

It is a further object to provide an improved dog-control mechanism for a latch, wherein the dogging function may be independently controlled from either side of the door to which the mechanism is applied.

It is a specific object to provide a unitary rosette-and-door-handle construction adaptable directly to control a latch mechanism and incorporating dogging means selectively operable from either side of a door.

It is another specific object to provide an improved latch-actuating unit incorporating dogging means and self-aligning parts, whereby upon adaptation to a latch mechanism slight axis misalignments may not impair a proper functioning.

It is still another specific object to provide an improved unitary latch-actuating mechanism and door handle and key-operated lock, wherein part of a dogging mechanism is operated by the lock and wherein the key to the lock may not be removed unless the part operated by the key is in its dogging position.

It is a further specific object to provide an improved dogging mechanism for a latch and utilizing two relatively movable yet independently operable parts which may dog the latch when mutually engaged.

Other objects and various further features of the invention will be pointed out or will occur to those skilled in the art from a reading of the following specification in conjunction with the accompanying drawings. In said drawings, which show, for illustrative purposes only, a preferred form of the invention:

Fig. 1 is a side view in partial section of a latch mechanism to which a novel unitary rosette and door knob have been applied in accordance with the invention;

Fig. 2 is an enlarged horizontal sectional view of the knob-and-rosette parts of the assembly of Fig. 1, taken more or less in the plane 2—2 of Fig. 1;

Fig. 3 is an end view of the device of Fig. 2, with the rosette case sectioned more or less in the plane 3—3 of Fig. 2, the parts of Fig. 3 being shown in a different relationship than in Fig. 2;

Fig. 4 is a fragmentary view of certain parts of

2

the structure of Fig. 2, the view being taken in the same sectional plane as that of Fig. 2, but with the parts in still another relationship;

Fig. 5 is a sectional view taken in the plane 5—5 of Fig. 2, and;

Fig. 6 is a sectional view taken in the plane 6—6 of Fig. 2.

Broadly stated, my invention contemplates an improved latch-dogging means which may be employed for the selective dogging of a latch from either side of a door. The dogging means may utilize two engageable yet relatively movable elements, one of which may be actuated from one side of the door and the other of which may be actuated from the other side of the door.

In the form to be described, a latch-actuating mechanism is selectively dogged, and this mechanism includes an axially slidible coupling member keyed at one end to a latch-spindle member and at the other end to a door-handle member, and all three members may be unitary in a rosette-and-knob assembly. The knob may carry a built-in key-operated cylinder lock arranged to determine axial placement of the coupling member in or out of possible engagement with the dogging member, and the means for actuating the dogging member may face toward the other side of the door, for engagement with suitable spindle means which may pass through the door.

Referring to the drawings, my invention is shown in application to a unitary rosette structure 10 with a transversely extending spindle 11 to engage the roll-back means 12 of a tubular-type latch 13. The latch 13 may be inserted in a single bore 14 from the edge of a door 15, and the latch front 16 may be sunk flush into the edge of the door 15 and held by mounting screws (not shown) in the conventional manner. Rotation

40 of the spindle 11 will be understood to cause gear means on the roll-back 12 to engage the rack 17 on a latch carriage, so as to withdraw the latch bolt 18. The latch case 13 may include openings, as at 19, at opposite sides thereof for the transverse passage of a further spindle 20 to operate dogging means of the invention. The latch 13 may be of a type disclosed in greater detail in my copending patent application Serial No. 748,703, filed May 17, 1947.

50 In accordance with the invention, I provide a novel structure external of the latch assembly 13 and adaptable thereto for the selective independent dogging of handle operation from either side of the door. This selective dogging function may be achieved by the use of two relatively dis-

placeable members, one of which may be actuated from one side of the door for displacement in or out of possible dogging engagement with the other member, and the other of which may be actuated from the other side of the door in or out of possible dogging engagement with the first member. In the form shown, one of these relatively displaceable members is in the form of a longitudinally travelling nut or coupling 21 which is locked (as by keying) against rotation relative to the spindle 11 and relative to the outside knob or handle 22. The keying may be achieved by interfitting square ends, as when flats such as the flats 23 of spindle 11 are inserted into a square-shaped socket 24 inside one end of the coupling member 21; in similar fashion, square flats 25 on the shank of the handle 22 may fit in a square socket 26 at the other end of the coupling member 21.

In order longitudinally to position the coupling member 21, it may be internally threaded for threaded engagement, as at 27, with a threaded member 28 which is shown to have a boss journaled in a bore 29 within the knob 22. The threaded member 28 is preferably axially fixed relatively to the knob 22 and to the spindle 11, but it is rotatable relatively to the knob 22 and, hence, relatively to the coupling member 21 and to the spindle 11. The member 28 may be axially located by abutment at one end of its threaded part with a shoulder 30 on the knob 22 and by the seating of a ball 31 between the spindle 11 and the threaded member 28. The ball 31 may be seated in generally spherical concave surfaces formed in the spindle 11 and in the threaded member 28. For actuating purposes, the threaded member 28 may include keying means, such as a longitudinally extending square hole 32, for engagement with an actuating spindle 33.

The assembly of the parts thus far described is, in the form shown, held together upon the crimping or rolling of an outer edge 34 of a rosette frame member or case 35. The frame member 35 may be formed with a cylindrical inner surface 36 slidably to support the outer cylindrical surface 36' of the coupling member 21, and an inwardly extending flange or lip 37 may ride upon or support a suitable bearing surface 38 of the knob 22. A snap ring 39 seated in a groove in the surface 38 may serve to retain the handle or knob 22 and the rosette frame member 35 in assembled relation.

The rest of the rosette frame may include a back cover-plate member 40 having a flange held by the beaded or rounded edge 34 and formed with an inner cylindrical surface 41 slidably to support the outer cylindrical surface 42 of the coupling member 21 (see Fig. 4). At its inner end the cylindrical part of the frame member 40 may also include an inwardly directed lip or flange 43 to engage the circular rim 44 on the head of spindle 11. It will be appreciated that when assembled between the rosette frame members 35-40, the spindle 11, the ball 31, the threaded member 28, and the knob 22 may all be axially located with respect to each other; and, should there be any misalignment upon installing the rosette, that is, should the knob axis be slightly cocked or eccentric with respect to the axis of the roll-back 12 or the latch mechanism, a slight clearance or freedom between the square keying surfaces 24-23 may permit proper centering on the ball 31.

Thus far, I have described only the working parts which account for longitudinal positioning

of the coupling member 21. It will be appreciated that such longitudinal positioning may be produced upon the relative rotation of the knob 22 and of the actuating spindle 33, as by turning the key 50 of a cylinder lock 51, which may be mounted within the knob 22 and assembled with the spindle 33. The cylinder lock 51 may be of conventional construction and include a plug 52 to ride in a suitable counterbore 53 within the handle 22. The plug 52 and, hence, the cylinder lock 51 may be fixedly retained within the knob 22 when a spring-urged pin 54 on the plug 52 drops into an annular groove 55 in the counterbore surface, as will be understood. In accordance with practice, the knob shank may include a small hole (not shown) communicating radially with the groove 55, so that, when the key has been turned an appropriate amount to align the spring pin 54 with the said radial hole, a suitable tool may be inserted to depress the pin and permit axial removal of the lock 51 from the knob 22.

For a purpose which will later be clear, the plug 53 preferably carries an abutment, which may be a fixed pin 56 or other suitable abutment means, for abutment with a shoulder or the like 57 in the frame or body of the knob 22. The abutment means 56-57 will be understood to limit rotation of the key 50 in the lock 51, and the arrangement is preferably such that this limiting of abutment occurs when the key 50 is in position for withdrawal from the lock 51 and when the coupling member 21 is in a forward or dogging position, as will be more fully understood later. The abutment 57 will be understood to be above the plane of the drawing, in the sense of Fig. 2. Thus, for the arrangement shown, the abutment means 56-57 may prevent counterclockwise key rotation (as viewed from the side of the door from which the key is inserted) immediately after inserting the key. The only available freedom for the key 50 will then be for clockwise rotation, and the abutment means 56-57 will be understood to limit such rotation to less than one revolution of the key. The pitch or lead in the threaded member or screw 28 is preferably such as to produce a substantial longitudinal withdrawal of the coupling member 21 from the position shown in Fig. 2 to the position shown in Fig. 4, within a fraction of a revolution of the key 50, and, in the form shown, a double-lead thread on the screw 28 may produce such withdrawal in three-fourths of a revolution of the key.

Thus far, I have described merely the parts and the actuating means for positioning the threaded member or screw 28 and for positioning the coupling member 21, and I have indicated generally that the framework 35-40 of the rosette structure may incorporate dogging means actuatable independently of the movement of the coupling member 21 and accessible for actuation from the other side of the door, as by means of the dogging spindle 20 upon actuation of a control handle or lever 59. Such dogging means preferably includes a member that is shiftable in a sense different from the characteristic movement of the coupling member 21, and, in the form shown, a dogging projection 60 on a slideable dogging member 61 is generally transversely or radially slideable to engage a generally longitudinal groove 62 in the coupling member 21. The projection or dog 60 may be formed upon stamping out an enlarged oval opening 63 in the dogging plate 61, and such opening 63 is preferably sufficient to clear the outer cylindrical

surface 42 of the coupling member 21. The plate 61 may be guidingly supported between opposed parallel sides by means of chord plates or suitably formed shoulders 64-65 formed in or carried by the frame member 35 of the rosette.

For shifting purposes, the dog plate 61 may be eccentrically engaged with a gear member 68, as by means of a pin or other abutment means 66 on plate 61 projecting into a radially extending actuating slot 67 in the gear 68. The gear 68 may be annular with an inside diameter to derive free rotary and sliding support from the cylindrical surface 42 of the coupling member 21. In order to actuate the gear 68, a drive pinion 69 may mesh with gear 68, and pinion 69 may include suitable actuating means, such as a socket 70, to be engaged by the spindle 20.

In the position shown in Fig. 3, it will be appreciated that the dogging lever 59 has just been raised in order to crank the pinion 69 clockwise (in the sense of Fig. 3) and at the same time, to drive the annular gear 68 counterclockwise for a downward displacement of the pin 66 and, hence, of the dog 60. Such downward displacement will be understood to have drawn the dog 60 radially out of alignment with the slot 62 and out of possible dogging engagement with the coupling member 21. Upon depressing the dogging lever 59, the annular gear 68 will be driven clockwise so as to raise the dogging slide 61 and to engage the dog 60 with the slot 62 (or, rather, to place dog 60 in a position to engage the slot 62), thus producing the relationship of parts shown in Figs. 2 and 4 as far as the dog 60 is concerned.

In order to assure retention of one or the other of the two described positions of the dogging lever 59, any conventional snap-action means may be employed and, in the form shown, I provide spring means 72 with a gently rounded end to rest against a pin or other suitable abutment 73 carried by the plate 61. The spring 72 may be located by slipping it over one of the bosses 46 that is fixedly carried by the rosette frame member 35.

If desired, and for purposes of greater adaptability of my unitary rosette-and-handle construction, a further pinion gear 75, like the gear 69, may be in constant engagement with the ring gear 68 and may include a suitable socket 76 to engage a dog-actuating spindle 20' similar to the spindle 20, depending upon the mounting of the door. Both gears 69 and 75 may be formed with bosses or journal portions 77 to ride in suitable locating and supported holes 78, which may be punched at preferably diametrically opposite points in the rosette cover plate 40, as will be clear.

A better understanding of the above-described construction may be had from a brief operating description. Let it be assumed that the parts are in the relationship of Fig. 2, with the knob 22 on the outside of the door and with the dog 60 in engagement with the coupling member 21. In this relationship of parts, the inside knob (not shown), which may also drive the spindle 11, will be unable to operate the latch mechanism 13 because it will then be keyed to the coupling member 21, which, in turn, will have been dogged against rotation at 62. In order then to get out of the room, one must first operate the dogging lever 59 so as to shift the dog downwardly to the position shown in Fig. 3 and out of possible engagement with the slot 62 of the coupling member 21. This operation of the lever 59 will be

also understood to have freed the outside knob 22 for independent operation of the door-latch mechanism 13 from the outside of the door. Thus, to lock the door, it will be necessary deliberately to shift the lever 59 so as to place the dog 60 within the groove 62 (see Fig. 2), or in a position to engage the groove 62 (see Fig. 4).

Placement of dog 60 within the groove 62 will, of course, be understood to have dogged both the inside knob (not shown) and the outside knob 22 against operation of the latch mechanism 13, and it will be appreciated that the door cannot be opened from the outside until the key 50 is inserted in the lock 51 and until the lock 51 has been turned an amount sufficient to withdraw the coupling member 21 axially out of possible dogging engagement with the dog 60, as shown in Fig. 4. Since the key will not then have turned a complete revolution, and since the abutment means 56-57 will prevent one from turning the key a full revolution, it will not be possible to remove the key 50 as long as the relationship of parts shown in Fig. 4 still exists, and, of course, when the key has been operated in this manner, both handles for the spindle 11 may be freely operated. In order, then, to remove the key 50, it must be turned back into the position shown in Fig. 2, and this movement necessarily will compel a return of the coupling member 21 into dogging engagement, or at least into possible dogging engagement, with the dog 60. It will be noted that, in utilizing the key to open the door from the outside, there is no disturbance of the lock, as set from the inside; thus, the inside setting of the lock will not be changed either by key-operated opening of the door or by subsequently closing the door.

It will be appreciated that I have described an ingenious mechanism for application to a more or less conventional latch mechanism. My improved construction may be unitarily assembled of easily fabricated parts and thus may provide an inexpensive means for introducing selective dogging functions in a latch mechanism. The dogging functions may be independently controlled from both sides of the door, and, when one of these functions is key operated, the key may not be removed unless the door is locked from the outside. My mechanism will function well in spite of careless misalignment in mounting to a door, and the fact that both the independently controlled dogging elements are operated by threaded or gear means will be understood as indicating a long life for the structure.

While I have described my invention in detail for the preferred forms shown, it will be understood that modifications may be made within the scope of the invention as defined in the following claims.

60 I claim:

1. In a latch device of the character indicated, latch-actuating means, two relatively movable interengageable dogging members for dogging said latch-actuating means when in engagement with each other, means including an axially fixed rotatable member actuatable from one side of the latch for moving one of said members into and out of a dogging position, and means including an axially fixed rotatable member actuatable from the other side of the latch for moving the other of said members into and out of a dogging position, whereby the latch may be undogged upon an operation from either side.

2. In a device of the character indicated, an outside knob, a cylinder lock in said knob, an out-

7 side rosette, and means on the inside for holding said rosette against a door, a latch-actuating spindle keyed to said knob at all times, dogging means in said rosette and including two independently and relatively movable dogging members movable into and out of mutual engagement, said knob being dogged only when said members are in engagement with each other, means operated by said lock for moving one of said members relatively to a position in which it may be engaged by the other of said members, and means operable from the inside for moving the other of said members relatively to a position in which it may be engaged by said one member.

3. In a device of the character indicated, an outside knob, a cylinder lock in said knob, an independently longitudinally movable coupling member including a dog element carried thereby, said coupling member being arranged at all times to couple said knob to a latch spindle to be actuated, a further independently movable dog element movable to engage said first dog element and to dog said coupling member when in engagement with said first dog element, and connecting means between said coupling member and said lock for longitudinally moving said coupling member out of the dogging position.

4. A device according to the claim 3, in which means operable from the inside are connected to operate said further dog element out of its dogging position.

5. In a latch device of the character indicated, rotatable latch-actuating means for hand operation at both sides of a door, dogging means for said latch-actuating means for selective operation from either side of the door, said dogging means including an independently and generally longitudinally movable member and an independently and generally transversely movable member, said members being movable into and out of engagement with each other and dogging said latch-actuating means when in engagement with each other, means actuatable from one side of the door for moving one of said members relatively to its dogging position, and means actuatable from the other side of the door for moving the other of said members relatively to its dogging position.

6. As an article of manufacture, a rosette assembly for application to a door-latch mechanism, said assembly including rotatable and longitudinally movable latch-actuating means engageable with the latch mechanism, independently movable dogging means doggingly engageable with said latch-actuating means in one longitudinal position of said latch-actuating means and free of said latch actuating means in another longitudinal position of said latch-actuating means, axially fixed rotatable means accessible from one side of the door and in longitudinally propelling engagement with said latch-actuating means for selectively longitudinally positioning said latch-actuating means out of possible dogging engagement with said dogging means, and means accessible from the other side of the door for actuating said dogging means.

7. In a rosette assembly of the character indicated, a spindle for engagement with a latch, manual-actuating means for said spindle, longitudinally slid able coupling means keyed both to said spindle and to said manual actuating means, means threadingly engaging said coupling member for longitudinal placement of said coupling member and longitudinally positioned between said spindle and said manual means, and dogging means transversely movably engageable with said

5 coupling member in one longitudinal position thereof for dogging said coupling member against rotation, said dogging means being free of said coupling member when said coupling member is in another longitudinal position, said threaded means being actuably accessible from the side on which said manual means is located and independent of said manual means.

10 8. In a rosette assembly of the character indicated, longitudinally slid able rotatable latch-actuating means, dogging means including a generally transversely movable portion for dogging said latch-actuating means against rotation, said dogging means being engageable with said latch-actuating means in one longitudinal position of said latch-actuating means and out of engagement therewith in another longitudinal position of said latch-actuating means, a knob keyed to rotate with said latch-actuating means, threaded means 15 rotatable relatively to said knob and in threaded engagement with said latch-actuating means, and a key-operated lock in said knob and including means engaging said threaded means, whereby said latch-actuating means may be longitudinally positioned in and out of dogging engagement upon key operation of said lock.

20 9. A device according to claim 8, in which abutment means cooperating between a rotatable part of said lock and said knob serve to limit key-operated rotation of said threaded means, whereby the key for said lock may be removed only when said latch-actuating means is positioned for a dogging operation.

25 10. In a rosette assembly of the character indicated, rotatable latch-actuating means including manual means for operation from the side of the door on which the rosette is mounted, dogging means for dogging said latch-actuating means against rotation, said dogging means including a member slidably guided in the frame of said rosette and including a projection to dog said latch-actuating means, a gear rotatable on the axis of said latch-actuating means and including means to engage a part of said slid able member for a forcible displacement of said slid able member upon rotation of said gear, a further gear meshing with said first gear and supported for rotation on an axis offset from the axis of said latch-actuating means, said second gear 30 including means actuably accessible from the other side of the door, whereby said slid able member may be selectively dogged to said latch-actuating means from the side of the door opposite said manual means.

35 11. A device according to claim 10, in which said latch-actuating means has a longitudinally extending groove open at one axial end thereof for engagement with a part of said slid able member, and in which said latch-actuating means is 40 longitudinally slid able, whereby upon a longitudinal sliding of said latch-actuating means said groove may be positioned in or out of engagement with said slid able member when said slid able member has been set for the dogging engagement.

45 12. In a latch device of the character indicated, a latch spindle, manual means for operating said latch spindle, a threaded member axially positioned between said spindle and said manual member and rotatable relatively thereto, a coupling member longitudinally slidably keyed to both said spindle and said manual means and in threaded engagement with said threaded member, and dogging means for said coupling member.

13. A device according to claim 12, in which said spindle and said threaded member are formed with concave seats and in which a ball is supported between said seats, whereby there may be slight malalignment of the axes of the said threaded member and of said spindle without impairing the cooperating functions of these elements.

14. In a latch device of the character indicated, latch-actuating means including a spindle, dogging means for said latch-actuating means and including two relatively movable interengageable members, each of said members being independently movable in and out of a dogging position, said members being engaged to each other when in dogging position, said latch-actuating means being dogged only when said members are in engagement with each other, means actuatable from one side of a door for moving one of said members relatively to the dogging position thereof, and means actuatable from the other side of the door for moving the other of said members relatively to the dogging position thereof.

15. In a latch device of the character indicated, a longitudinally displaceable rotatable latch-actuating element having means at opposite ends for non-rotatable longitudinally slid-

able engagement with respect to a manual actuating member and with respect to a latch-actuating member, abutment means on said latch-actuating element, dogging means movable into and out of engagement with said abutment means for one longitudinal position of said latch-actuating element, said latch-actuating element being free of said dogging means for another longitudinal position of said latch-actuating element, and axially fixed rotatable means actuatable to longitudinally displace said latch-actuating element.
